UNITED STATES PATENT OFFICE.

NORMAN V. CHRISTENSEN, OF CHICAGO, ILLINOIS, ASSIGNOR TO UNION SPECIAL MACHINE COMPANY, OF CHICAGO, ILLINOIS, A CORPORATION OF ILLINOIS

FILLED-BAG SEWING MACHINE.

Application filed December 31, 1921. Serial No. 526,116.

The invention relates to new and useful improvements in sewing machines, and more particularly to a sewing machine for closing the mouth of a filled bag.

5 An object of the invention is to provide a machine of the above type wherein the bag is stationary and the mouth thereof supported in proper position for stitching, and wherein the stitching mechanism travels across the 10 bag mouth during the stitching thereof.

A further object of the invention is to provide a machine of the above type, wherein the sewing machine is mounted on a carriage which in turn is mounted on ball bearing 15 wheels, so that the carriage may be propelled across the mouth of the bag by the feed dog of the sewing machine itself.

20 A further object of the invention is to provide a sewing machine of the above type, wherein the mouth of the bag is supported by a rail extending across the machine in a direction parallel with the tracks and between the overhanging arm of the sewing machine and the work support, and wherein 25 said rail is provided with supporting devices adapted to engage and support the mouth of the bag.

20 A still further object of the invention is to provide a supporting table for bags of 30 large sizes, which table is adjustable so that the weight of the bag may rest on the table while the mouth of the bag is held supported by the rail for the sewing machine to travel across and stitch the same.

35 These and other objects will in part be obvious and will in part be hereinafter more fully disclosed.

40 In the drawings which show by way of illustration one embodiment of the invention—

Figure 1 is a front view of a filled bag sewing machine embodying my improvements;

45 Figure 2 is a sectional view on the line 2—2 of Fig. 1;

Figure 3 is a sectional view on the line 3—3 of Fig. 1;

Figure 4 is a sectional view on the line 4—4 of Fig. 1;

50 Figure 5 is a detail showing the lever for applying a brake to the belt wheel of the sewing machine and carrying the controlling switch for the motor;

Figure 6 is a view of the parts shown in Fig. 5 as seen from the right thereof;

The invention is directed broadly to a filled bag machine having a supporting frame preferably consisting of two spaced uprights which are connected by tracks adjacent the upper end thereof and a brace rod adjacent the lower end thereof. Mounted to move back and forth on the tracks is a carriage which in turn is mounted on ball bearing 55

wheels so as to reduce to a minimum the power necessary to propel the carriage. 60 These tracks are horizontal. Mounted on the carriage is a sewing machine of the ordinary construction having an overhanging arm and a work support, a stitching mechanism and a feeding mechanism. The feeding mechanism operates upon the material to feed the machine across the mouth of the bag during the stitching and the carriage travels from one side of the machine to the other.

65 Also, mounted on the uprights is an adjustable table on which bags of large sizes may be supported. This table can be set at different heights to accommodate the size of the bag being stitched. Also, fixed to the uprights is a rail which extends between the 70

overhanging arm and the work support and above the path of reciprocation of the needle. This rail is provided with suitable supporting devices which engage the mouth of the bag and hold the same while the 75 stitching mechanism travels across the mouth of the bag.

80 Referring more in detail to the drawings, my improved filled bag sewing machine comprises two spaced standards 1 and 2. Each 85 standard is mounted in a supporting base bracket 3, which in turn is carried by castors 4—4. These supporting base brackets 90

95 are connected by a rod 5, which extends through the bracket and nuts 6 threaded on to the brace rod clamping the opposite faces of the brackets. This makes a rigid spacing support for the uprights. Each upright is provided with a bracket head 7. The 100 bracket head 7 has two upwardly projecting arms 8 and 9, see Fig. 2, which are connected by a cross bar 10. Mounted in the arm 8 is a tubular rail 11. Also, mounted in the arm 9 is a tubular rail 12. It is understood that 105 these tubular rails extending from one bracket head to the other are rigidly secured

thereto and form a rigid connection for the upper ends of the uprights.

Mounted to travel back and forth on the rails 11 and 12, which form a track, is a carriage 13. The carriage 13 includes a supporting frame 14 with a downwardly projecting bracket 15, see Fig. 2. The frame 14 is preferably mounted on three wheels 16, 17 and 18. In Figure 3, I have shown a sectional view through the wheel 17. These wheels are all similarly mounted. Carried by the frame 14 of the carriage 13 is a shaft 19 which projects laterally therefrom. Mounted on said shaft 19 is a collar 20. Also mounted on the shaft and at the end of the collar is a ball bearing 21. A retaining collar 22 is then slipped on the end of the shaft and the parts are held thereon by means of a nut 23. The wheel 17 is formed with a concave periphery 24, which is adapted to fit the curvature of the tubular rail 11. Each wheel is similarly formed and mounted and this provides a simple form of carriage which travels back and forth on the track formed by the rails 11 and 12. The three wheeled carriage will be firmly supported by the rails and at the same time will be very readily moved on the rails owing to the ball bearings for the wheels.

Mounted on the depending bracket 15 is the sewing machine head 25. Said sewing machine head 25 includes the usual overhanging arm 26, the usual tubular work support 27, a stitching mechanism of which the reciprocating needle bar 28 is illustrated, the usual presser foot and feeding mechanism, the feeding mechanism being located in the work support 27 and including a four-motion feed dog 27^a of the usual type.

Mounted on the upright 1 is a sleeve 29 which is adapted to slide freely on the upright. This sleeve carries a bracket 30, preferably formed integral therewith, which bracket includes a horizontal arm 31 and a vertical arm 32. Also mounted on the upright 2 is a similar sleeve 29' which carries a bracket 30' provided with a horizontal arm 31' and a vertical arm 32'. Extending between the arms 31 and 31' is a table 320. Said table is bolted to the arms by means of bolts 33—33. Also carried by the arms 32 and 32' is a support 34 which is secured to the bracket arms by means of suitable screw bolts 35. The sleeves 29 and 29', as above noted, are adapted to slide freely on the uprights 1 and 2 and may be clamped in any desired position by means of a set screw 36 having a crank handle 37, whereby said screw may be turned.

As a means for adjusting the table 320 up and down, I have provided sprocket chains 38, one at each side of the machine and these sprocket chains run over sprocket wheels 39 and are connected to counter-bal-

ancing weights 40. The sprocket wheels 39 are mounted on a shaft 41 extending from side to side of the machine and journaled in suitable brackets 42 carried by the bracket heads 7—7. A crank 43 is attached to the shaft 41 for turning the same. It will be noted from the above that the counterweights practically counter-balance the weight of the table so that it may be readily raised and lowered when said screws have been released and thus the table positioned at any desired height. It will also be noted that the table projects forwardly from the uprights 1 and 2, so that it is readily accessible for the placing of the filled bag thereon and the sewing machine overhangs said table. The stitching line is substantially midway between the extreme front and rear ends of the table so that when the filled bag is placed on the table and rests against the support 34, the mouth of the bag will be properly positioned for the sewing machine to travel across the same.

Extending between the overhanging arm 90 and the work support is a supporting rail 44. Said supporting rail 44 is rigidly secured to bracket arms 45 by means of bolts 46, see Fig. 4. The bracket arms 45 surround the uprights and are each secured thereto by a set screw 47. This supporting rail 44 is held in fixed position, although it may be adjusted up and down, if desired. Carried by the supporting rail 44 and at suitable spaced distances along the same are supporting hooks or pins 48. These hooks or pins are preferably rigidly secured to the rail by means of bolts 50, see Fig. 4. The hooks or pins 48 are so positioned as to height that the mouth of the bag may be hooked thereon and thus supported, and while the mouth of the bag is thus supported the sewing machine may travel across the mouth of the bag and form a line of stitching therein. In Figure 1, I have shown a filled bag B in broken lines, resting on the table 320 and secured by the hooks 48 and the line of stitching s in dotted lines, which has been formed by the sewing machine as it travels across the mouth of the bag in the direction indicated by the arrow in said figure.

The stitching mechanism and feeding mechanism of the machine are operated by a suitable driving shaft carrying a belt wheel 51. A motor 52 is mounted on the carriage and a belt 53 running over the driving wheel of the motor and the driving wheel 51 of the sewing machine rotates the main shaft thereof. Said driving belt runs over idlers 54, see Fig. 2. Mounted on the supporting bracket 15 is a lever 55. Said lever is pivoted at 56 to said bracket and capable of being moved in a horizontal direction. This lever carries a switch block 57 which is op-

erated by the finger pieces 58. Said switch block is connected to wires L leading to the motor and said motor can be stopped and started by means of this switch block 57.

5 Mounted on the lever 55 is a brake shoe 59 which is adapted to engage the flange of the driving wheel 51 for stopping the sewing machine when the current is cut off. It will readily be seen that the operator by grasping 10 the handle 60 of the lever 55 can control the switch and can move the lever so as to cause the driving shaft of the sewing machine to stop. The lever 55 is provided with a projecting toe 61 which serves to 15 limit the movement of the lever in an outward direction away from the driving wheel of the sewing machine.

While I have described the machine as particularly adapted for filled bags which are supported by the table 320, it is understood that in case the bags are small, the supporting hooks or pins 48 alone may be sufficient to support the entire weight of the bag, in which case the table 320 would 20 not be necessary. I have also illustrated, therefore, in Figure 1 a small filled bag B' which is indicated as having been stitched by a line of stitching s'.

It is thought that the operation of my machine will be obvious from the description which has been given above. When operating upon comparatively heavy filled bags, the table 320 is adjusted to the proper height so that the mouth of the bag may be supported by the pins or hooks 48, while the bottom of the bag rests on the table 320 and supports the contents of the bag. The carriage is moved to the extreme left of the bag before the bag is put in place and then 30 the operator brings the sewing machine to a point where the extreme left-hand side of the mouth of the bag is underneath the presser foot and clamped against the feed dog. As the machine is started the feed 40 dog will intermittently engage the fabric forming the mouth of the bag and as the bag is held stationary by the supporting rail 44, the machine itself will move one step to the right and thus it is that the sewing machine 45 is caused to travel from left to right across the mouth of the bag, stitching the same. Owing to the fact that the carriage is mounted on ball bearing wheels and the rails are horizontal, or substantially so, the 50 feed of the sewing machine can readily cause the carriage to move step by step.

It will be noted that the bracket which carries the sewing machine extends downwardly between the rails forming the track 60 to a considerable distance so that the center of weight of the bracket and sewing machine

is well below the tracks and this will cause the carriage to firmly rest on the track as it moves back and forth.

It will be obvious that minor changes in 65 the details of construction and the arrangement of the parts may be made without departing from the spirit of the invention as set forth in the appended claims.

Having thus described my invention, what 70 I claim as new and desire to secure by Letters Patent, is:—

1. A filled bag sewing machine comprising a supporting frame structure, a track carried by said supporting frame structure, a carrier mounted on said track and freely movable back and forth thereon, a sewing head mounted on said carrier and depending therefrom, a motor mounted on said carrier and connected to the sewing head for operating the same, said track being substantially horizontal whereby the feed of the sewing head operating upon the filled bag will move the carrier along said track, and a stationary 75 filled bag support associated with said supporting frame structure.

2. A filled bag sewing machine including in combination, a supporting frame, a track mounted on said supporting frame, a carrier mounted on said track and movable back and forth on said track in a straight line, a sewing head rigidly mounted on said carrier and having a stitching mechanism and a feeding mechanism, including a feed dog, said sewing head depending from the carrier and adapted to stitch the mouth of a filled bag supported beneath said track, said track being substantially horizontal whereby the feed dog of the sewing machine operating upon the fabric of the filled bag may be utilized for moving the carrier during the stitching of the bag.

3. A filled bag sewing machine including in combination, a supporting frame, a track mounted on said supporting frame, a support for the bag mounted on the frame beneath the track, means for raising and lowering the support, a carrier mounted on said track and freely movable back and forth thereon in a straight line, a sewing head mounted on said carrier and having a stitching mechanism and a feeding mechanism including a feed dog, said sewing head depending from said carrier and adapted to stitch the mouth of a filled bag supported beneath said track, said track being substantially horizontal whereby the feed dog operating upon the filled bag may be utilized for moving the carrier during the stitching of the bag.

In testimony whereof, I affix my signature.

NORMAN V. CHRISTENSEN.
